UNITED STATES PATENT OFFICE.

OSCAR W. RICHARDSON, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

WEFT-REPLENISHING MECHANISM.

Application filed January 18, 1924. Serial No. 687,102.

To all whom it may concern:

Be it known that I, OSCAR W. RICHARDSON, a citizen of the United States, residing at Worcester, in the county of Worcester and State of Massachusetts, have invented a new and useful Weft-Replenishing Mechanism, of which the following is a specification.

This invention relates to weft replenishing mechanism of the type employing vertical stacks of spare bobbins and has more particular reference to means for controlling the passage of spare bobbins from the stacks to transfer position.

In a type of multi-color replenishing mechanism which has gone into extensive use the bobbins are arranged in vertical stacks and are supported by so-called cradles, one of which is provided for each stack. When a bobbin is to be transferred it is moved to a position under and between the stacks of the bobbins so as to be centrally located with respect thereto and it has been found that the bobbins originating from the outermost stacks do not roll smoothly down the inclined guideways which lead to the transfer point. The reason for this is that the butt of the bobbin strikes the inclined guide and rebounds, thus interfering with the free movement of the bobbin. The tip of the bobbin continues to move without interruption and the resulting unequal motion of the ends of the bobbin presents the bobbin under the transferer arm with its axis oblique with respect to the axis of the shuttle. Under such circumstances the transferer is likely to break either the bobbin or the shuttle and it is a general object of my invention to provide improved means by which the butt of the bobbin can be passed to the transfer position without striking and rebounding from the guideway.

Another object of my invention is to provide a bobbin cradle so constructed as to give adequate support to the bobbin but at the same time provide for the auxiliary or additional guideway which is associated with the principal guideway.

With these and other objects in view which will appear as the description proceeds, my invention resides in the combination and arrangement of parts hereinafter described and set forth in the claims.

Referring to the drawings,

Fig. 1 is a fragmentary end elevation of the inner frame of a weft replenishing mechanism showing my invention applied thereto,

Fig. 2 is a view similar to Fig. 1 but with the parts in a different position,

Fig. 3 is a horizontal section taken on line 3—3 of Fig. 1, and

Fig. 4 is a section taken on line 4—4 of Fig. 1.

Referring more particularly to the drawings it will be seen that the inside frame 10 of the replenishing mechanism is provided with flanges 11 defining guideways for the butts or heads of the bobbins. Associated with each pair of flanges 11 is a cradle 12 the inner end of which is rotatably mounted on the frame 10 by means of stud 13. Said cradle is provided with two supporting arms, arm 14 extending from the body of the cradle to afford a pivotal connection with the stud 13 and arm 15 extending parallel to the arm 14 but offset therefrom. Formed integrally with the frame 10 is a guideway 16 which is spaced from arm 15 and is formed with an upper guide surface 17. The frame 10 is also provided with a boss 18 which receives the stud 13 and is located between the arms 14 and 15.

The parts previously described may be of the usual construction except for the length of arm 15.

As heretofore constructed the guideway 16 has been made substantially as wide as the butt of the bobbin and the arm 15 of the cradle has been made long enough to extend entirely under the butt of the bobbin and terminating in close proximity to the inner face 19 of the frame. This construction has resulted in the formation of a projecting corner on the guideway 16 against which the rings of the bobbin strike as the latter passes out of the cradle to transfer position. It has also been customary to carry the boss 18 back to the face 19 of the frame 10 and the gap between said boss 18 and the adjacent corner of the guideway 16 has made it possible for a bobbin to fall against said guideway 16 below the plane of the face 17 and to rebound, this rebounding acting to retard the motion of the bobbin toward transfer position.

In order to prevent this rebounding I

have provided a web 31 cast integrally with the frame 10 and extending between the guideway 16 and the boss 18, said web having a surface 30 which merges with the surface 17. As shown in Fig. 1 the cradle 12 has been turned to receive the lowermost bobbin of the associated stack and is awaiting the return of the indicating shuttle, the arm 15 serving to retain the lowermost bobbin B as shown. Fig. 2 represents the position of the parts when the indicating shuttle is about to return to transfer position, the cradle 12 having been returned to normal position. The result of this is to lower arm 15 so that the bobbin B is released to pass to transfer position. Because of the fact that surface 30 merges with surface 17 it will be seen that the bobbin is effectively held away from the corner 32 of the boss 16 and the bobbin moves to transfer position with a smooth rolling motion which is uninterrupted, thus avoiding the objectionable rebound heretofore experienced.

By referring to Fig. 4 it will be seen that surface 30 of the web 31 is slightly tapered and is raised above the plane of the surface 17, the purpose of this being to afford a support for the wooden portion of the bobbin which extends beyond the rings R. In this way the rings are directed to glide smoothly onto the face 17.

From the foregoing it is apparent that I have provided a very simple means by which a bobbin is directed to the principal or primary guideway 16 by means of the auxiliary or secondary guideway 31, the result of which is to move the cradle to transfer position without subjecting the same to obnoxious rebounding. Also it is apparent that this result is attained without interfering with the normal function of arm 15 in supporting the bobbin.

Having thus described my invention it will be apparent that changes and modifications may be made therein by those skilled in the art without departing from the spirit and scope of the invention and I do not wish to be limited to the details herein disclosed, but what I claim is:

1. In a weft replenishing mechanism for looms, means defining a guideway for spare

bobbins, a primary guideway to direct the bobbin to transfer position, releasing means for the lowermost bobbin having an arm extending between the bobbin and the guideway, and a secondary guideway extending from the primary guideway toward said releasing means and effective to engage a portion of the butt of the bobbin as it is released by said arm and to guide the same continuously to the primary guideway.

2. In a weft replenishing mechanism for looms, means defining a vertical guideway for spare bobbins, a primary guideway to direct bobbins to transfer position, releasing means at the bottom of said guideway to engage the lowermost bobbin, an arm formed with said releasing means to engage that portion of the bobbin adjacent the guideway, and a secondary guideway of less width than the primary guideway to engage a portion of the bobbin to guide the same to the primary guideway.

3. In a weft replenishing mechanism for looms, means defining a guideway for the bobbins, a releasing device to receive a bobbin located at the bottom of the guideway, a primary guide spaced from said releasing device and the bobbin when the latter is in the releasing device, and an auxiliary guide to direct the bobbin continuously during its entire movement from said releasing means to the primary guide.

4. In a weft replenishing mechanism for looms, means defining a vertical guideway for spare bobbins, a bobbin releasing device located at the bottom of the guideway, a primary guide surface to direct the bobbins to transfer position and arranged to engage the rings of the bobbins, and a secondary guide surface positioned between the releasing device and the primary guideway, and effective to continuously engage the end portion of the released bobbin beyond its bobbin rings until said bobbin is supported by said primary guiding surface, said secondary surface being higher than the primary surface.

In testimony whereof I have hereunto affixed my signature:

OSCAR W. RICHARDSON.
